DESIGN FOR A DISPLAY STAND

Hans A. Hansen and Solomon R. Salkin,
Peoria, Ill.

Application December 6, 1943, Serial No. 111,930

Term of patent 14 years

To all whom it may concern:

Be it known that we, Hans A. Hansen and Solomon R. Salkin, both citizens of the United States, residing at Peoria, in the county of Peoria and State of Illinois, have invented a new, original, and ornamental Design for a Display Stand, of which the following is a specification, reference being had to the accompanying drawing, forming part thereof.

The figure is a perspective view of a display stand, showing our new design.

We claim:

The ornamental design for a display stand, as shown.

HANS A. HANSEN.
SOLOMON R. SALKIN.
